UNITED STATES PATENT OFFICE.

CHARLES E. HOOSE, OF INDIANAPOLIS, INDIANA.

LUBRICATING SYSTEM.

Application filed December 1, 1925. Serial No. 72,507.

This invention pertains to a lubricating system for the wedges employed in an adjustable driving box for locomotive driving wheels.

In locomotive driving wheels, the supporting axle is mounted in a bearing positioned in what is termed a driving box. The driving box is held in position in a suitable frame by a so-called floating wedge and a so-called adjusting wedge. Heretofore there has been some difficulty experienced in lubricating these wedges, and various arrangements have been employed for this purpose.

It is the object of this invention to provide means for automatically lubricating the wedges under pressure caused by the rotating action of the axle within the bearing. This is found to give a very satisfactory and desirable lubrication without the attention which has heretofore been required from the engineer.

The full nature of the invention will be understood from the accompanying drawings and the following description and claims.

Fig. 1 is a central vertical section through the driving box and wedges. Fig. 2 is a section taken on a line 2—2 of Fig. 1. Fig. 3 is the same as Fig. 1 showing a modified form thereof. Fig. 4 is a section taken on a line 4—4 of Fig. 3.

In the drawings there is shown a portion of the framework 10 of a locomotive in which there is mounted a driving box in which a suitable bearing is provided for the axle 12 of the driving wheel. The driving box 11 is provided with a suitable opening through which the axle extends, and positioned immediately above the axle, so as to conform thereto, is a bronze bearing member 13. Below the axle there is a perforated retaining plate 14, for the lubricant reservoir, said plate conforming in curvature to the axle and mounted adjacent the lower surface thereof. Said plate is adapted to retain a cake of grease 15 which is pressed against the perforated plate 14 of the lubricant reservoir by the bottom plate 16 under spring pressure produced through the medium of the compression spring 17. This is of the usual structure and causes the axle to be constantly lubricated by means of the spring 17 gradually squeezing the lubricant contained in the waste through the perforated plate 14.

In order to adjustably maintain the driv-

ing box in position within the frame, there is provided a so-called floating wedge 18 comprising a metal plate positioned adjacent the side of the box and tapering in cross section from the top to the bottom. Adjacent the floating wedge 18 there is an adjusting wedge 19 mounted on the opposite side thereof from the box, comprising a similar plate tapering in cross section from the bottom to the top, the tapering of the adjusting wedge 19 being much more pronounced than that of the floating wedge. The adjusting wedge is held in adjusted position through the medium of the rod 20 extending upwardly through the frame from the bracket 21 in which it is adjustably mounted under spring tension through the medium of the spring 22 and spring pocket 23. This structure as above described is old and commonly used in practice. The difficulty heretofore has been in suitably lubricating the wedges 18 and 19.

To that end, this invention contemplates that the bearing member 13 be provided with an oil receiving recess 24 in its bearing surface, said recess leading into an upwardly extending passageway 25, extending upwardly through the bearing member and the upper portion of the driving box, and adapted to be closed by the valve screw 26. There may be a plurality of such holes extending through the top portion of the bearing member and box as illustrated in Fig. 2. Communicating with one or more of said upwardly extending openings there are laterally extending passageways 27 leading to each side of the box for conducting such lubricant as may be discharged therethrough to the side surfaces thereof.

It will be noted that one of the passages, as illustrated in full lines in Fig. 1, leads to that side of the box adjacent the floating wedge 18, communicating with a relatively large opening 28 therein. On each side of the wedge 18 there are vertical lubricating grooves 29 which will carry a lubricant received in the opening 28 downwardly along the surfaces thereof to be distributed over said surfaces by capillary attraction in the usual manner. The adjusting wedge 19 is likewise provided with an opening 30 and vertical lubricating grooves 31 communicating therewith, the opening 30 being partially in registry with the opening 28, whereby the lubricant received in the opening 28 may pass into the opening 30 and lubricate the surfaces of the adjusting wedge.

By means of this arrangement, it is found in actual practice that the rotation of the axle 12, which is well lubricated from the grease in the reservoir 15 will deposit a substantial portion of the lubricant carried about the surface thereof in the pocket formed by the groove 24. Such lubricant will be forced upwardly through the passage 25 by reason of the centrifugal force caused 10 by the rotation of the axle. The pumping force applied thereto being such as to distribute the lubricant through the various passageways, openings and grooves above mentioned, under sufficient pressure to thoroughly lubricate the bearing surfaces of the wedges and driving box without requiring any attention, as has heretofore been required in such structures.

The valve screws 26 and 126 are so arranged as to extend into the passageways 27 and 127 respectively so as to control the flow of lubricant therethrough. It is quite possible that the surfaces would be over-lubricated and lubricant wasted wherein a free passage was left, but by means of the valve screw, the passage of the lubricant thereby can be so adjusted and regulated as to permit only sufficient lubricant forced to the surfaces as will be necessary to provide sufficient lubrication.

Wherein the structure is herein shown as being provided with two wedges, in some cases only a single wedge is employed, the same being termed a "straight wedge" structure. This invention contemplates the lubrication of the surfaces of the driving box by means of the above described arrangement, as well as wherein either a single or "straight wedge" is used or a floating and adjusting wedge as shown herein.

In the modified form shown in Figs. 3 and 4, the principle involved is the same, however the lubricant is pumped or forced through the tubular passageways 137 to the openings 128 and 130 formed substantially midway of the wedges 18 and 19.

It is to be noted, that in the actual use of this lubricating system, the heat created at the top of the axle causes the lubricant forced into the passage 25 and retarded by the valve 26, to boil. This gives a beneficial action to the lubricant which facilitates its passageway to the bearing surfaces in a vaporized or volatile condition, such as assists its penetration to said surfaces.

The invention claimed is:

1. The combination with a driving box for receiving the axle of locomotive driving wheels, and a wedge therefor, of a lubricating system comprising a lubricant containing reservoir adapted to feed the lubricant to the surface of the axle and an upwardly extending conduit positioned in said box having one end communicating with the upper bearing surface thereof, and a conduit hav-

ing one end communicating with the upper end of said upwardly extending conduit and communicating with the surface of said wedge whereby lubricant carried by the axle will be consistently forced through the action thereof upwardly through said conduit and directed to the surface of the wedge for lubricating the same. 70

2. The combination with a driving box for receiving the axle of locomotive driving wheels and a plurality of wedges therefor, of a lubricating system comprising a lubricant containing reservoir adapted to feed the lubricant to the surface of the axle and an upwardly and laterally extending conduit positioned in said box having one end communicating with the upper bearing surface thereof, and with the adjacent surfaces of said wedges whereby lubricant carried by the axle will be consistently forced through the action thereof upwardly through said conduit and directed to the surfaces of the wedges for lubricating the same. 75

3. The combination with a driving box for receiving the axle of locomotive driving wheels, of a lubricating system comprising a lubricant-containing reservoir adapted to feed the lubricant to the surface of the axle, an upwardly extending conduit having one end communicating with the upper bearing surface of said box, conduits extending from the other end and communicating with the outer surface of the box, whereby lubricant carried by the axle will be consistently forced through the action thereof upwardly to said conduit and directed to the outer surface of the box for lubricating the same, and means on said box extending into one of said conduits adapted to restrict the passage of lubricant therethrough so as to cause the same to boil from the heat and pressure exerted by the action of the axle and pass to the surface to be lubricated in a volatile condition. 100

4. The combination with a driving box for receiving the axle of locomotive driving wheels, of a lubricating system comprising a lubricant containing reservoir adapted to feed the lubricant to the surface of the axle, a conduit having one end communicating with the surface of said axle and the outer end thereof communicating with the outer surface of said box, whereby the lubricant carried by the axle will be continuously forced through the action thereof through 115 said conduit to the outer surface of said box for lubricating the same, and an adjustable valve extending into said conduit adapted to restrict the passage of lubricant therethrough so as to cause the same to be heated from the heat and pressure exerted by 120 action of the axle for facilitating its passage to the surface to be lubricated. 125

5. The combination with a driving box for receiving the axle of locomotive driving 130

- wheels, of a lubricating system comprising a lubricant containing reservoir adapted to feed the lubricant to the surface of the axle, a conduit having one end communicating with the surface of said axle and the outer end thereof communicating with the outer surface of said box, whereby the lubricant carried by the axle will be continuously forced through the action thereof through said conduit to the outer surface of said box for lubricating the same, and means extending into said conduit adapted to restrict the passage of lubricant therethrough so as to cause the same to be heated from the heat and pressure exerted by the action of the axle for facilitating its passage to the surface to be lubricated.
6. A device of the class described comprising a housing, a journal box in the housing, an axle in said journal box, a pair of reversely positioned wedges between the outside of said journal box and said housing, lubricating ports extending through each wedge, lubricating channels or grooves in the faces of said wedges, a passage leading from the inside of said box to the adjacent wedge, and means for supplying lubricant to said axle whereby the axle carries a portion of the lubricant to the journal box passage from which it passes to the passages and channels in the wedges, and the wedge sage from which it passes to the passages and channels in the wedges, and the wedge

channels retain sufficient lubricant to take care of lubrication between the wedges and adjacent surfaces, in the event the main supply becomes exhausted or stopped up. 35

7. A device of the class described comprising a housing, a journal box in the housing, a crown brass for said journal box, an axle in said journal box, a pair of reversely positioned wedges between the outside of said journal box and said housing, lubricating ports extending through said wedges, lubricating channels formed in the faces of said wedges, a passage leading from the inside of said journal box to the adjacent wedge, 40 a passage from the inside of said crown brass to the outer face thereof, and means for supplying lubricant to said axle whereby the axle carries a portion of the lubricant to the journal box passage from which it passes to the passages and channels in the wedges, and the wedge channels retain sufficient lubrication to take care of lubrication between the wedges and adjacent surfaces in the event the main supply becomes 45 exhausted or stopped up, and lubricant is also carried through the passage in said crown brass for lubricating the outer face thereof. 50

In witness whereof I have hereunto affixed my signature.

CHARLES E. HOOSER.
